UNITED STATES PATENT OFFICE.

FREDERICK V. SALISBURY, JOHN F. SALISBURY, AND AMON C. SALISBURY, OF
BLANDINSVILLE, ILLINOIS.

PUMP.

1,179,224.

Specification of Letters Patent.

Patented Apr. 11, 1916

Application filed May 7, 1915. Serial No. 26,579

To all whom it may concern:

Be it known that we, FREDERICK V. SALISBURY, JOHN F. SALISBURY and AMON C. SALISBURY, citizens of the United States, residing at Blandinsville, in the county of McDonough and State of Illinois, have invented certain new and useful Improvements in Pumps; and we do hereby declare the following to be a full, clear, and exact description of the invention, such as will enable others skilled in the art to which it appertains to make and use the same.

This invention relates to new and useful improvements in pumps, and has for its principal object to provide a pump of the double-acting type which may be easily operated and which is capable of developing considerable power in order that water may be lifted for great distances.

Another object of the invention is to provide an automatic means for reversing the movement of the pump piston which may be timed so that a number of strokes may be obtained relative to a single revolution of the pump operating wheel.

A further object of the invention is to provide a device which may be hand or power operated at the desire of the user.

30 Still another and more specific object of the invention is to provide a novel form of valve for the inlet ends of the cylinders.

With these and other objects in view, the invention consists in the novel combination and arrangement of parts which will be fully set forth in the following specification and accompanying drawings, in which,

Figure 1 is a view in elevation of a pump constructed in accordance with this invention showing a portion thereof in section to more clearly illustrate the details of construction, Fig. 2 is a view in elevation illustrating the operating mechanism on an enlarged scale, of the upper portion of the pump, Fig. 3 is a vertical sectional view through the pump cylinder illustrating the construction thereof, Fig. 4 is a sectional view taken on the line 4—4 of Fig. 3, Fig. 5 is a detail sectional view of a modified form of valve, Fig. 6 is a horizontal sectional view illustrating the detail construction of the operating mechanism and automatic reversing means, Fig. 7 is a view of one of the cam wheels, Fig. 8 is a view of a modified form of cam wheel, Fig. 9 is a view similar to Fig. 8 of a

still further modified form of cam wheel, Fig. 10 is a detail elevational view of a modified form of reversing gear showing a portion thereof broken away to more clearly illustrate the details of construction, Fig. 11 is a sectional view of Fig. 10, Fig. 12 is a detail perspective view of the sleeve used in the device illustrated in Fig. 10, Fig. 13 is a transverse sectional view through the sleeve, Fig. 14 is a view illustrating a modified form of pump pistons and cylinders, Fig. 15 is a plan view of one of the pistons used in the cylinder, Fig. 16 is a plan view of the valve used in connection with the piston, and Fig. 17 is a plan view of the assembled pistons and valve.

Referring to the drawings by characters of reference the numeral 1 designates the top casing in which the pipe 2 is held. This pipe is supported centrally of the casing by means of the collars 3 and 4, and the collar 4 is secured in the casing by means of the set screws 5. The upper end of the pipe terminates in the nozzle 6, while the lower end is secured to the connection 7 which leads to the pump cylinders 8 and 9. The connection 10 which is located at the lower portion of the cylinder, is connected centrally to the feed pipe 11 through which the water is drawn from the bottom of the well. 75 80 85

The pump cylinders 8 and 9 hereinbefore referred to, are best illustrated in Fig. 3 and are provided with the valve designated generally by the numeral 12, which comprises the stem 13, which stem is slidable in the spider 14 formed in the horizontal portion of the connection 10. Secured to each end of the stem are the valve heads 15 which engage the ends of the connection 10 and close the opening on the down stroke of the pump piston. 95

The modified form of valve, which is best illustrated in Fig. 5, comprises the sleeve 16 which is slidable on the stem 13 and is provided with the flange 17 against which the gasket 18 rests. A suitable washer 19 surrounds the sleeve and is held in place by means of the nut 20 which is threaded on the end of the sleeve opposite the flange 17. A suitable coil spring 21 is interposed between the flange 17 and the nut on the end of the stem 13, and this coil spring is arranged to force

the valve toward the center of the stem. It will thus be seen that except during the up stroke of the pump pistons, the valve will remain closed.

5 The pump pistons, which are designated by the numerals 22, are secured to the ends of the piston rod 23 and are provided with suitable valves 24 which coöperate with the valve 12 in forcing the flow of 10 water from the bottom of the well into the pump. The upper ends of the piston rods terminate in the angular portions 25 which are braced by the rectangular frames 26, and these angular portions are connected 15 at their upper terminals to the pump rods 27, which in turn terminate at their upper terminals in the outwardly extending arms 28, to which the rack bars 29 are adjustably secured. These rack bars are 20 provided with the teeth 30 which are arranged to mesh with the gear and pump operating mechanism which will be more fully hereinafter described.

The gear and operating mechanism hereinbefore referred to, is best illustrated in Fig. 6 and comprises the supporting arm 31 carrying the cross piece 32, which cross piece is formed with uprights 33 in which the shaft 34 is journaled. This shaft 34 carries the spur gear 35 and is formed intermediate its ends with the squared portion 36 on which the sleeve 37 is slidably mounted. Suitable beveled gears 38 and 39 are mounted on the shaft and are independently 35 rotatable thereon, and each of these gears is formed with a clutch half 40 with which the clutch halves carried by the ends of the sleeve 37 coöperate. A suitable groove 42 is formed in the sleeve and a fork 43 carrying lugs 43' is formed on the lever 44, which lever is pivoted to the frame 32 as at 45. The lugs 43' extend into the groove and are arranged to slide the sleeve so as to bring the clutch halves alternately into and 40 out of engagement, and thereby alternately drive the gears 38 and 39. It will be noted that the free end of the lever 44 extends into the groove in the cam wheel so that upon rotation thereof the lever will be oscillated. 45 These gears 38 and 39 mesh with the crown gear 46 which is rotatably mounted on the stud 47, which stud is mounted on the upright 48 carried by the frame 32. A suitable crank 49 is secured to the face of the 50 gear 46 and is provided with the handle 50 by which the device is set in operation. Suitable guides 51 are mounted laterally of the gear 35 and are arranged to hold the rack bars 29 in operative relation with the 55 gear.

In order that the sleeve 37 will be moved, the cam wheels illustrated in Figs. 7, 8 and 9, are provided and comprise the circular body 52 which is formed with the cam track 53. This cam track may be in the form

shown in any of the Figs. 7, 8, or 9, and when the form illustrated in Fig. 9 is used, it will be apparent that the gear 42 will be shifted from one side to the other twice during a single revolution of the crown gear 46. When the cam wheel, illustrated in Fig. 8, is used, it will be apparent that the sleeve will be shifted three times during a single revolution, and when the cam wheel illustrated in Fig. 7 is used, the sleeve will be shifted four times during a single revolution of the crank. It will thus be seen that the number of the strokes of the pump piston per revolution may be regulated so as to provide a means for increasing or decreasing the speed of the movements of the pump piston without changing the speed of the drive wheel 46. These cam wheels are 70 removably held within the crown gear 46 by means of the bolts 54, and it will thus be 75 apparent that they are interchangeable so that any number of combinations of cam grooves may be provided.

In the modified form of the device, illustrated in Figs. 10, 11, 12, and 13, instead of the shaft 34 being formed with a squared portion 36, the sleeve, designated generally by the numeral 55, is provided with a suitable set screw 56 by which the same is secured to the shaft 34. This sleeve 55 comprises the body 57 which is formed at each end with the reduced extensions 58. Both the sleeve and the reduced portions 58 are formed with the central longitudinal opening 59 for the reception of the shaft 34, and formed in the reduced extensions 58 are the grooves 60 which align with the longitudinal opening 61 formed in the body 57. These grooves and this opening 61 form a guide for the sliding bar 62, which is formed at each end with the lugs 63, the use of which will appear as the description proceeds. These lugs 63 extend diagonally across the outer face of the sliding bar 62 and are arranged to move the bar so that the reversal of the shaft will be insured. Co-operating with the sleeve and the sliding bar 62 are the clutch members 63' which are secured to the inner faces of the gears 38 in place of the clutch halves 40 described and shown hereinbefore. Each of these clutch members 63' comprises the circular body 64 which is formed with the peripheral flange 65. These members are secured in any suitable manner to the gears, and the bodies 64 are provided with the openings 66, while the flanges 65 are formed with the internally screw threaded, screw-receiving openings 67 in which the set screws 68 are mounted. These set screws 68 are arranged to engage the lugs 63 so as to shift the bar 62 into the openings 66 when the device is in operation.

It will be apparent from the foregoing that in use when the crank 50 is turned, the

wheel 46 will be driven and thereby cause the gears 38 and 39 to revolve freely on the shaft 34 in opposite directions. The rotation of the gear 46 will cause the cam wheel 52, carried by bolts 54, to revolve and thereby move the lever 44 so as to slide the sleeve 37 and bring the clutch halves on the sleeves alternately into engagement with the clutch halves on the opposite gears, and thereby drive the shafts in opposite directions. It will be apparent that since the gear 35 is secured to the shaft 34, the same will be alternately driven in clockwise and counter-clockwise directions, thereby causing the rack bars to alternately rise and fall, thereby operating the pump rods and pistons. During the rising of the pistons in the cylinders it will be apparent that the valves 15 will be lifted from their seats and thereby permit the inflow of liquid to the cylinders.

In the operation of the modified form of reversing gear, it will be evident that upon rotation of the gear 46, the gears 38 will be set in motion and when the bar 62 is in one of the notches in the clutch member 63 in the gear on the left hand side, it will be evident that the shaft will be driven in the direction of the rotation of the gear 38, until the set screw 68 in the clutch member 63', which is secured to the gear 39, engages the lugs 63 on the end of the rod 62 opposite the end adjacent the gear 38, at which time the rod 62 will be slid longitudinally through the grooves 60 and the opening 61 so that it engages in one of the openings 66 in the clutch member 63' carried by the gear 39. It will thus be seen that the direction of rotation of the sleeve and shaft 34 will be reversed so that the operation of the pump pistons will be alternately up and down.

In the modified form of pump cylinders and piston arrangements, the two pistons are operable in a single cylinder as clearly shown in Fig. 14. The pump cylinder is designated by the numeral 69 and is provided at its lower end with the shaft 70, the lower end of which has threaded thereinto, the pipe 71 which communicates with the bottom of the well. A suitable spider 72 is located in the upper end of the pipe and is provided with a central sleeve 73 which acts as a guide for the stem 74 of the valve 75. The upper end of the cylinder 69 is provided with the cap 76, having formed therein, a central aperture 77 and a pair of outlet openings 78 in which the lower ends of the pipes 79 are threaded. The upper ends of these pipes are connected by means of the pipe connection 80 to the stand pipe 81, which leads to the body of the pump. Slidable through the central opening 77 in the cap 76 is the hollow pump rod 82, the lower end of which is provided with the hollow squared portion 83 and carries the pump piston 84 which is best illustrated

in Fig. 15 and is formed with three openings 85 located at points equi-distant from each other as clearly shown. Slidable on the squared portion 83 of the hollow pump rod 82 is the valve 86 which is best illustrated in Fig. 16 and is provided with three equi-distant apertures 87 and the rectangular central opening 88 which is arranged to receive the squared portion 83 of the pump rod 82 and form a guide for the valve so that the openings 87 will be held out of registration with the openings 85. The upper end of the pump rod 82 extends through the opening 77 as hereinbefore described and vertically through the center of the stand pipe 81 to the pump operating mechanism best illustrated in Figs. 1 and 2 and this hollow pump rod may be connected in any suitable manner to be actuated by the spur gears 35. Slidable through the hollow pump rod 82 is the solid pump rod 89, the lower end of which is provided with the squared portion 90 and carries the pump piston 91 which is constructed similar to the piston 84. Slidable on the squared portion 90 of the pump rod 89 is the valve 92 which like the valve 86 is formed with openings which do not register with the openings in the pistons 91. The upper end of the pump rod 89 is slidable through the hollow pump rod 82 and is connected in any suitable manner to the operating wheel 35, so that when the pump rod 82 and piston 84 descend the pump rod 89 and piston 91 will ascend, thereby forcing the liquid between the piston up through the opening in the piston 84 into the upper part of the cylinder 69. It will thus be seen that a double action single cylinder pump is provided which will maintain a substantially continuous flow of water through the stand pipe and pump when the same is in operation.

While in the foregoing there has been shown and described the preferred embodiment of this invention, it is to be understood that such changes may be made in the combination and arrangement of parts as will fall within the spirit and scope of the appended claims.

What is claimed is:

1. In combination, cylinders, pistons operable in the cylinders, pump rods connected with the pistons, rack bars at the upper ends of the pump rods, a gear meshing with the rack bars, a supporting frame, a shaft rotatable in the frame, the gear being rigid on the shaft, a pair of gears loosely mounted near opposite ends of the shaft, a drive gear meshing with the gears, a sleeve splined on the shaft, a clutch half at each end of the sleeve, clutch halves on the loosely mounted gears co-operating with the clutch halves on the sleeve, and means carried by the drive gear to alternately move the clutch halves into engagement with the loosely mounted

gears and thereby reverse the rotation of the gear with which the rack bars coöperate.

2. In combination, a double acting pump, rack bars operably connected with the pump, 5 a spur gear meshing with the rack bars a supporting frame, a shaft journaled in the supporting frame, the spur gear being rigid on the shaft, gears loosely mounted near each end of the shaft, a sleeve splined on 10 the shaft, a clutch half carried by each of the loosely mounted gears, a clutch half at each end of the sleeve, a crown gear meshing with the loosely mounted gears, means to drive the crown gear, a fork controlling

the longitudinal movement of the sleeve, 15 and a cam wheel carried by the crown gear automatically controlling the movement of the fork to slide the clutch halves alternately into and out of engagement with the loosely mounted gears. 20

In testimony whereof we affix our signatures in presence of two witnesses.

FREDERICK V. SALISBURY.
